UNITED STATES PATENT OFFICE.

JAMES F. DURYEA, OF SPRINGFIELD, MASSACHUSETTS, ASSIGNOR TO STEVENS-DURYEA COMPANY, OF CHICOPEE FALLS, MASSACHUSETTS, A CORPORATION OF MASSACHUSETTS.

CARBURETER-VALVE.

1,100,291.

Specification of Letters Patent. Patented June 16, 1914.

Application filed March 12, 1912. Serial No. 683,817.

To all whom it may concern:

Be it known that I, JAMES F. DURYEA, a citizen of the United States, residing at Springfield, in the county of Hampden and State of Massachusetts, have invented certain new and useful Improvements in Carbureter-Valves, of which the following is a specification.

This invention relates to improvements in carbureter valves.

It has for its object the construction of an improved valve of the type known as "needle valves" for use in connection with spray nozzles of the type of carbureter most used in the present gas engine practice.

A further object of this invention is to provide a needle valve for use in connection with a spray nozzle which will give a definite increase of gasolene supply for equal movements of the needle valve.

Other objects of my invention will be apparent as set forth in the following specification and accompanying drawings, in which—

Figure 1 is a side elevation of my improved needle valve and a section of part of the spray nozzle in connection therewith; Fig. 2, a cross section on the line 2, 2 of Fig. 1; and Fig. 3, a diagrammatic view showing the method of plotting the curve for the form shewn.

Like numerals and reference letters refer to like elements throughout the drawings.

10 designates a conventional form of supply tube terminating in a spray nozzle 11, as shown in Fig. 1. In employment of this spray nozzle, liquid is normally automatically kept at a certain level by a float or other means not shown, and air rushing 40 through a surrounding intake pipe and around said supply tube 10 and spray nozzle 11 causes the amount of gasolene or other fuel to be drawn out of said spray nozzle and mixed with the air. The amount of 45 gasolene drawn out will obviously be increased or decreased as the opening 12 is increased or decreased. To regulate the size of this opening it has been common practice to provide a valve terminating in a conical 50 point and adapted to close said spray nozzle at one extremity of its movement and entirely open the same at its other extremity.

In my improved device I provide a needle valve 15 having the valve body 16 with

an enlarged head 17 at its upper portion 55 provided with bifurcated arms 18 having apertures 19 therein through which may be passed a pivot to pivotally secure said needle valve 15 to a moving means such as a lever. I have shown my needle valve 15 60 as terminating at its other extremity in a shank 20. This shank 20 is formed thereon for convenience in cutting the body 16 of the needle valve 15 to the shape desired and may be ground off to cause the lower extremity of the needle valve 15 to terminate, as indicated by the dotted line 21, if so desired.

The valve 15 and spray nozzle 11 preferably have a common longitudinal axis, as 70 shown in Fig. 1 of the drawings. The valve 15 is normally adapted to be moved longitudinally of said axis either into or out of said spray nozzle 11, as will be apparent in the drawings. I have constructed 75 my body valve 16 in such a way that for successive equal movements of said needle valve 15 into or out of said spray nozzle 11 the successive annular openings at 12 will be proportionally increased or decreased 80 respectively. This ratio of increase or decrease may be chosen to provide for the most efficient and economical operation of a carbureter. In my experience, however, I have found that this ratio of increase gives good 85 results when each successive annular opening at 12 differs from the preceding opening by one-tenth of the annular opening upon a longitudinal movement of the valve equal to 1/28 the total movement thereof. 90 That is, for a movement of the valve body 16 from the position shown in Figs. 1 and 2 to the next successive opening, (from point a to point b,) the annular opening at 12 will be increased by one-tenth. In other 95 words, as shown in Fig. 2, the annular opening 12 is increased by the slight annular opening indicated as lying between the dotted circle b' and the full line circle a' representing the successive cross sections of the 100 valve body 16 through the points a and b. By thus proportioning the valve body it is obvious that a construction much more advantageous than that ordinarily used is provided, since it is readily apparent 105 when the conical form of needle valve is used equal successive movements of the conical valve, outwardly for example, will give

varying increase to the annular opening so that in the movement of a throttle controller, such as is ordinarily used, equal distances, no proportional increase is obtained 5 in the amount of gasoline sprayed at the spray nozzle.

In constructing the body 16 of my needle valve 15 to comply with the conditions desired, as enumerated above, I find that the 10 longitudinal cross section, as indicated by the outer periphery of the body 16 in Fig. 1, will be a curve convex with respect to the lines *d* and *e* drawn from the maximum diameter at *c* in Fig. 1 to the point of minimum diameter, as indicated at *f* in the construction shown in Fig. 1. In other words, 15 the sides of a cone having for its base the maximum cross section at *c* of the needle valve 15 and having sides passing through 20 the point of minimum cross section, that is at the point *f* in the construction shown, will lie wholly within the body 16 of the needle valve 15. Also, the longitudinal cross section of the body 16 of the valve 15 will 25 be convex with respect to a cone situated as above stated. If the body 16 were ground or cut off at the lower extremity, as indicated along the dotted line 21, the contour of the longitudinal cross section of the needle valve in that form would show a completed figure, following out the formula for 30 designing the same. When the shank 20 is allowed to remain at the lower extremity of the valve 15, the spray nozzle 11 is so 35 constructed as to give a maximum opening therethrough for the service intended when the shank 20 lies in such nozzle, that is, when the body 16 of the valve 15 is in its maximum opening position.

40 In Fig. 3 I have shown the curve plotted for the form as illustrated in Figs. 1 and 2, the revolution of which, about its longitudinal axis, will give the configuration of the body 16 of the valve 15, as shown in Fig. 1.

45 It is to be noted that in these figures I have shown the spray nozzle in greatly exaggerated form. The successive longitudinal movements I have shown in constructing this illustrated form are approximately 1/28 50 of the total movement of the valve, although this may be varied. The successive annular

openings vary about 1/10 of each preceding opening, for the amount of longitudinal movement chosen in this case as indicated by the series of successive values in the dia- 55 grammatic showing of Fig. 3. It is to be noted that while in the drawings I have shown the successive longitudinal movements as of a certain distance and the total movement divided in 28 steps, these are arbitrarily selected here to aid in establishing one form of the valve for a certain ratio of increase. It is obvious that this form may be varied to comply with desired variations 60 or conditions.

65 It is believed that the purpose and operation of my improved device is made sufficiently clear in the above specification to obviate the requirement of any further description. I do not desire to restrict myself 70 to the exact form or dimensions shown in the drawings beyond the scope of the appended claims.

I claim:

1. The combination of a spray nozzle having 75 a circular aperture, and a needle valve adapted to move in and out of said aperture, said needle valve being so designed that for successive equal movements thereof successive annular openings between said valve 80 and said spray nozzle will be increased or decreased in a definite ratio.

2. The combination of a spray nozzle having 85 a circular aperture, and a needle valve adapted to move in and out of said aperture to regulate the amount of gasoline flowing therethrough, said needle valve having its longitudinal axis in common with that of the spray nozzle and being adapted to move longitudinally of said axis, the body of said 90 needle valve being so constructed that for successive equal movements thereof the successive annular openings between said valve and said spray nozzle will be increased or decreased in a definite ratio.

95 In testimony whereof, I have subscribed my name.

JAMES F. DURYEA.
